3,277,100 NOVEL SUBSTITUTED PYRAZOLES

Clifford L. Dickinson, Jr., Wilmington, Del., assignor to E. I. du Pont de Nemours and Company, Wilmington, Del., a corporation of Delaware
No Drawing. Filed May 31, 1963, Ser. No. 284,374
15 Claims. (Cl. 260—294)

This invention relates to pyrazole derivatives and more particularly refers to 3-amino-4-cyano-N-carbamyl-pyrazoles and their preparation.

According to this invention I have discovered a narrow class of substituted pyrazoles having a most unusual combination of pharmacological properties.

I have found that this valuable combination of properties is obtained, for reasons which are not understood or yet fully explained, only with a small group of pyrazole compounds where there must be a cyano substituent in the 4-position of the pyrazole ring and also there must be an amino or acylamino substituent of 1 through 3 carbons in the 3-position (or 5-position but not both the 3 and the 5; it is critical that one of these positions must be unsubstituted except for hydrogen).

Thus, the compounds of this invention have the formula:

which can exist as the isomeric formula

where

X is oxygen or sulfur;

R₁ is methyl;

R₂ is alkyl of 1 through 6 carbons where the alkyl is joined to the carbamyl nitrogen by a primary or secondary carbon of the alkyl group; alken-2-yl of three through 6 carbons where the alken-2-yl group is joined to the carbamyl nitrogen by a primary or secondary carbon of the alken-2-yl group; alkoxyalkyl of 2 through 6 total carbons; hydroxyalkyl of 2 through 6 carbons; dimethylamino; or dialkylaminoalkyl where each of the alkyl groups in the dialkyl portion has 1 or 2 carbons and the remaining alkyl group has 1 through 4 carbons with a total of from 3 through 7 in the dialkylaminoalkyl group;

and where R₁ and R₂ can be joined together and together with the carbamyl nitrogen form a heterocyclic structure from the following group:

2

mono-substituted piperidyl of the structure

where Y₁ is H or CH₃; Y₂ is H, CH₃, C₂H₅ or COOR₅ where R₅ is alkyl of 1 through 4 carbons; and Y₃ is H, alkyl of 1 through 6 carbons, hydroxyalkyl of 2 through 6 carbons, trifluoromethyl, COOR₆ where R₆ is alkyl of 1 through 4 carbons, dialkylaminoalkyl of 3 through 7 carbons where each of the alkyl groups in the dialkyl portion has 1 or 2 carbons and the remaining alkyl group has 1 through 4 carbons, pyrrolidinoethyl or arylalkyl of 7 through 9 carbons including such groups as benzyl, phenethyl, and o-, m- and p-tolylethyl; and disubstituted piperidyl of the structure

where Y₂ and Y₃ have the same meaning as above; and R₃ can be hydrogen but it is much more highly preferred that it is an acyl radical of 1 through 3 carbons such as formamido, acetamido and propionamido. Of the compounds of Formula 1 where R₂ is alkyl or alken-2-yl, it is preferred that the alkyl or alken-2-yl group is joined to the carbamyl nitrogen by a secondary carbon of the alkyl or alken-2-yl group.

The compounds of this invention are generally solids. They can be used as inhibitors for vinyl polymerization but are particularly useful for their physiological characteristics.

Because of their excellent analgesic activity and other desirable pharmacological properties, the preferred compounds of Formula 1 are carbamyl pyrazoles where X is oxygen and where R₁ and R₂ are joined to form a piperidino ring and in particular a mono-substituted piperidyl ring where the substituent is in the para position with respect to the carbamyl nitrogen. Thus, preferred compounds of this invention include the following exemplary ones:

- 50 1-N-(4-methylpiperidino)carbonyl-3(5)-formamido-4-cyanopyrazole
1-N-(4-methylpiperidino)carbonyl-3(5)-acetamido-4-cyanopyrazole
1-N-(4-methylpiperidino)carbonyl-3(5)-propionamido-4-cyanopyrazole

Also preferred are those compounds of Formula 1 where R₂ is alkyl of 1 through 4 carbons, such as methyl, ethyl, n-propyl, isopropyl, n-butyl, sec-butyl, etc. Illustrative of these preferred compounds are the following:

- 60 4-cyano-1-N,N-dimethylcarbamyl-3(5)-formamidopyrazole
3(5)-acetamido-4-cyano-1,N,N-dimethylcarbamyl-pyrazole
65 4-cyano-3,(5)-formamido-1-N-isopropyl-N-methylcarbamylpyrazole
3(5)-acetamido-4-cyano-1-N-isopropyl-N-methylcarbamylpyrazole
1-N-sec-butyl-N-methylcarbamyl-4-cyano-3(5)-formamidopyrazole
70 3(5)-acetamido-1-N-sec-butyl-N-methylcarbamyl-4-cyanopyrazole

The substituted carbamyl pyrazoles of this invention can be prepared by reaction of the appropriate pyrazole with selected reactants as more fully described below.

One general method for the preparation of the pyrazoles of this invention can be carried out where the amine-N-carboxyl chloride (e.g., N,N-dimethylcarbamoyl chloride) is available. In this process there are brought together approximately equimolar amounts of the pyrazole and the chloride in an unreactive solvent such as ether, ethyl acetate, or benzene, together with an equimolar amount of a base such as sodium hydride or triethylamine. The resulting mixture is refluxed for an extended period, say up to about 24 hours or more, and allowed to cool. The insoluble chloride e.g. sodium chloride or triethylamino hydrochloride, is filtered off and the solvent is removed from the filtrate to give the desired carbamyl or thiocarbamyl pyrazole product.

The same general procedure as just described is used when the pyrazole-1-carbonyl chloride is available (e.g., from pyrazole having hydrogen on nuclear nitrogen and either phosgene or thiophosgene) except that the secondary amine is reacted with the pyrazole carbonyl chloride. The first method is preferred if the 3-aminopyrazoles are used since the 3-amino group would react with the phosgene or thiophosgene, whereas the second method is preferred for amines such as N-methyl-N-hydroxyethylamine where the amine substituent can also react with the phosgene or thiophosgene.

The amine carbonyl chlorides such as N-piperidine carboxyl chloride are prepared by placing in a flask fitted with a "Dry-Ice" condenser, mechanical stirrer and dropping funnel preferably at least 1.2 moles of phosgene in an inert solvent such as ether, tetrahydrofuran, benzene, ethyl acetate or the like. A solution of 1 mole of the selected amine, e.g., piperidine, and preferably, for increased yields, with 1 mole of tertiary amine such as triethylamine, in the selected solvent is added slowly with stirring and the temperature is kept below 30° C. with occasional cooling. When all of the amine has been added, the mixture is stirred several hours. The mixture is filtered to remove the hydrochloride and the solvent is removed from the filtrate by boiling it off. The remaining amine-N-carboxyl chloride is distilled under reduced pressure to effect purification.

Alternatively, the pyrazole can be used in the above procedure in place of the amine (piperidine). By this procedure, with 3-acetamido-4-cyano-pyrazole, one obtains 3-acetamido-4-cyano-pyrazole-1-carbonyl chloride.

As mentioned above, the compounds of this invention have outstanding activity as analgesics, many of them exceeding codeine in potency, as shown by standard animal tests. This analgesic activity in these compounds is particularly valuable because of significantly favorable therapeutic ratios. General painkilling benefits, as well as other physiological benefit associated with aspirin, are believed to be obtainable according to this invention based on tests and evaluation thus far carried out.

Furthermore, the compounds of this invention exhibit outstanding anti-inflammatory and central nervous system activity.

In pharmaceutical application a compound of this invention will be administered to the body orally, parenterally and by other methods. The dosage will vary and will depend on such factors as the condition being treated; age and weight of the recipient; the responsiveness of the recipient; prior, concurrent and intended subsequent, medication and treatment, general health of the recipient; frequency of treatment; and of course the purpose and nature of the effect desired.

Generally speaking, the active compound will be administered in a physiologically beneficial amount. Administration can be in a single dose or in a plurality of doses over an extended period of time. It will furthermore be understood that every compound within this in-

vention does not have an identical level of dosage requirement for therapeutic or prophylactic effectiveness and therefore experts will understand that some dosage variation between compounds can be expected for maximum benefits. It will of course also be understood that an initial dose, or first group of doses, in a course of treatment can be in greater amounts, if appropriate, for a particular medical situation and a rapid response is sought by the early administration of relatively large doses and thereafter the minimally effective dosage, or maintenance dosage, is determined.

A single dose will rarely exceed about 400 or 500 milligrams of active compound within this invention, although larger amounts can be used as called for in any given situation. Extremely small doses will effect some benefit but as a practical matter a single dose of less than about 1 or 2 milligrams will seldom be used. For treating small animals with high physiological response and using highly active compounds, routine usage can be at much lower dosage levels however. Doses can be repeated in the same or greater or lesser amounts over a period of time as long as improvement in the recipient is observed or as long as needed under the circumstances.

The active compound will ordinarily be administered with a non-toxic pharmaceutical carrier in a variety of practical dosage forms. These dosage forms are novel compositions comprising the non-toxic pharmaceutical carrier and a physiologically beneficial amount of one or more active compounds of this invention. These highly useful dosage forms constitute an important aspect of the present invention.

Suitable non-toxic pharmaceutical carriers or vehicles include liquids such as water, aromatic water, alcohols, syrups, elixirs, pharmaceutical mucilages, such as acacia and tragacanth, oils such as of petroleum, animal, vegetable or synthetic origin, for example, peanut oil, soybean oil, fish oil such as cod liver oil, or the like, for oral administration; water, saline, aqueous propylene glycol, aqueous polyethylene glycol, aqueous lactose, aqueous maltose, aqueous glucose (dextrose), aqueous sucrose, or the like, for administration by injection. Suitable solid carriers include soft gelatin capsules, hard gelatin capsules, slow or delayed release pills or capsules, powders, tabletting vehicles and the like. Suitable solid or liquid non-toxic pharmaceutical carriers are well known in the art and the selection of carrier can be from those appropriate and available in accordance with well known prescription techniques. The compositions of this invention therefore include such dosage forms as solution, suspensions, syrups, elixirs, tablets, capsules, powder packets, and the like.

A vast number of suitable pharmaceutical carriers are described in "Remington's Practice of Pharmacy" edited by E. W. Martin and E. F. Cook, 12th Edition, 1961, published by the Mack Publishing Company, Easton, Pennsylvania.

In these novel compositions the active ingredient of Formula 1 or 2 will be present in a physiologically beneficial amount as mentioned above. In practice this means that the active ingredient will ordinarily constitute at least about 0.01% by weight based on the total weight of the composition. For oral administration in water or other liquid medium, the concentration will ordinarily be in the range from about 0.5 to 5.0% by weight of active ingredient. For injection concentrations from 2 to 20% are satisfactory. In tablets, powders, capsules and the like the amount of active ingredient may if desired be as much as 90 to 95% or more by weight of the total composition.

The active compounds of this invention can be formulated if desired with one or more pharmaceutically active materials for combination effects, treatments and benefits. Such materials include but are by no means lim-

ited to vitamins, pain killers, tranquilizers, antibiotics, antitussive agents, etc. The compositions can of course contain suitable pharmaceutical modifiers such as coloring agents, sweetening or other flavoring agents, solubilizing agents, etc. as will readily occur to persons skilled in this art.

This invention will be better understood by reference to the following illustrative examples in which parts and percentages given are by weight unless otherwise indicated.

EXAMPLE 1

3(5)-amino-4-cyano-1-N,N-dimethylcarbamylpyrazole

A mixture of 20.4 grams of 3-amino-4-cyanopyrazole and 9.2 grams of sodium hydride in 100 milliliters of tetrahydrofuran is stirred 15 minutes. Dimethylcarbamoyl chloride (21.4 grams) is added and the mixture refluxed three hours, filtered and the filtrate evaporated to dryness. The solid remaining is recrystallized from ethyl acetate to give 6.8 grams of 3(5)-amino-4-cyano-1-N,N-dimethylcarbamylpyrazole, M.P. 134-137° C.

Analysis.—Calcd. for $C_7H_9N_5O$: C, 46.9; H, 5.1; N, 39.1. Found: C, 47.4; H, 5.1, N, 38.8.

The compound of this example exhibits excellent analgesic activity and is representative of the compounds of this invention in being characterized by extremely low acute toxicity as shown in standard animal tests. In combination with its other desirable pharmacological properties, this compound is a poor cholinesterase inhibitor and thus can be expected to give rise to little or no undesirable side effects.

The compound of this example furthermore exhibits anti-inflammatory activity. The compound is formulated conveniently as an injectible solution of 0.5%, 1% and 5% by weight concentration in isotonic saline; as an injectible solution in 0.5%, 1.0% and 5% by weight concentrations in aqueous sugars including in separate solutions lactose, maltose, glucose (dextrose) and sucrose; in water in 1%, 2%, 3% and 4% by weight concentration for oral administration, with and without a flavoring agent, a coloring agent, an antitussive agent, etc.; and in 25, 50, and 100 milligram amounts in standard two-piece sealed hard gelatin capsules, as well as in soft gelatin capsules, for oral administration. In pharmacological application it is administered in these dosage forms as dosage levels in the range of 25-500 milligrams.

EXAMPLE 2

3-acetamido-4-cyano-1-N-piperidinocarbonylpyrazole

A mixture of 15.7 grams (0.1 mole) of 3-acetamido-4-cyanopyrazole and 4.7 grams of sodium hydride (53% in oil) in 200 milliliters of dimethoxy ethane is stirred and refluxed 30 minutes. Pentamethylenecarbamoyl chloride (15.7 grams, 0.1 mole) is added in portions and the mixture is stirred and refluxed for 6 hours, then filtered hot. The precipitate that forms upon cooling is collected, yield 17.05 grams, M.P. 183.5-184.5° C. The filtrate is concentrated to about 75 milliliters and the precipitated collected upon cooling is 7.0 grams. A portion is recrystallized twice from ethyl acetate to give pure 3-acetamido-4-cyano-1-N-piperidino carbonylpyrazole, M.P. 183-184° C.

Analysis.—Calcd. for $C_{12}H_{15}N_5O_2$: C, 55.2; H, 5.8. Found: C, 55.2; H, 5.6.

The compound is formulated and used in 5, 10, and 25 milligram amounts in standard 2 piece hard gelatin capsules for oral administration. Appropriate amounts of corn starch or lactose can be used as a filler in the capsule.

The compound can also be formulated as a coated or uncoated tablet containing 2.5 to 50 milligram amounts and from 1 to 4% by weight of gelatin, from 0.5 to 1.5%

by weight of magnesium stearate or talc and a filler such as lactose or mannitol.

The general procedures of the above examples can be repeated using other 3-amino and 3-acylamino 4-cyano pyrazoles and appropriately substituted carbamoyl and thiocarbamoyl chlorides in place of the reactants of those examples to obtain the following listed exemplary compounds of this invention:

Example No.	Product
3	3-formamido-4-cyano-1-N,N-dimethylcarbamylpyrazole.
4	3-acetamido-4-cyano-1-N,N-dimethylcarbamylpyrazole.
5	3-propionamido-4-cyano-1-N,N-dimethylcarbamylpyrazole.
6	3-amino-4-cyano-1-N-methyl-N-ethyl-N-ethylcarbamylpyrazole.
7	3-propionamido-4-cyano-1-N-methyl-N-ethylcarbamylpyrazole.
8	3-amino-4-cyano-1-N,N-dimethylthiocarbamylpyrazole.
9	3-formamido-4-cyano-1-N,N-dimethylthiocarbamylpyrazole.
10	3-acetamido-4-cyano-1-N,N-dimethylthiocarbamylpyrazole.
11	3-formamido-4-cyano-1-N-methyl-N-ethylcarbamylpyrazole.
12	3-acetamido-4-cyano-1-N-methyl-N-isopropylcarbamylpyrazole.
13	3-acetamido-4-cyano-1-N-methyl-N-seobutylcarbamylpyrazole.
14	3-formamido-4-cyano-1-N-methyl-N-hexylcarbamylpyrazole.
15	3-acetamido-4-cyano-1-N-methyl-N-(penten-2-yl)carbamylpyrazole.
16	3-acetamido-4-cyano-1-N-methyl-N-(2-hydroxyethyl)carbamylpyrazole.
17	3-propionamido-4-cyano-1-N-methyl-N-methoxymethylcarbamylpyrazole.
18	3-formamido-4-cyano-1-N-methyl-N-methoxypropylthiocarbamylpyrazole.
19	3-acetamido-4-cyano-1-N-methyl-N-diethylaminoethylcarbamylpyrazole.
20	3-acetamido-4-cyano-1-N-methyl-N-allylcaramylpyrazole.
21	3-amino-4-cyano-1-N-methyl-N-(buten-2-yl)carbamylpyrazole.
22	3-formamido-4-cyano-1-N-methyl-N-ethoxypropylthiocarbamylpyrazole.
23	3-acetamido-4-cyano-1-N-methyl-N-dimethylaminothiocarbamylpyrazole.
24	3-formamido-4-cyano-1-N-methyl-N-isobutylcarbamylpyrazole.
25	3-amino-4-cyano-1-N-morpholinocarbonylpyrazole.
26	3-acetamido-4-cyano-1-N-pyrrolidinocarbonylpyrazole.
27	3-acetamido-4-cyano-1-N-pyrrolidino(thiocarbonyl)pyrazole.
28	3-formamido-4-cyano-1-N-piperidinocarbonylpyrazole.
29	3-formamido-4-cyano-1-N-dehydropiperidinocarbonylpyrazole.
30	3-acetamido-4-cyano-1-N-azabicyclononylcarbonylpyrazole.
31	3-acetamido-4-cyano-1-N-(3,4-dimethylpiperidino)carbonylpyrazole.
32	3-acetamido-4-cyano-1-N-p-tolylethylpiperidinocarbonylpyrazole.
33	3-formamido-4-cyano-1-N-m-methylpiperidinocarbonylpyrazole.
34	3-acetamido-4-cyano-1-N-p-trifluoromethylpiperidinocarbonylpyrazole.
35	3-acetamido-4-cyano-1-N-p-ethylpiperidino(thiocarbonyl)pyrazole.
36	3-propionamido-4-cyano-1-N-[p-(n-butyl)piperidino](thiocarbonyl)pyrazole.
37	3-acetamido-4-cyano-1-N-o-methylpiperidino(thiocarbonyl)pyrazole.
38	3-formamido-4-cyano-1-N-p-benzylpiperidinocarbonylpyrazole.
39	3-acetamido-4-cyano-1-N-(m-ethoxycarbonyl)piperidinothiocarbonylpyrazole.
40	3-formamido-4-cyano-1-N-(3-methyl-4-ethylpiperidino)carbonylpyrazole.
41	3-amino-4-cyano-1-N-[p-(n-propyl)piperidino]carbonylpyrazole.
42	3-acetamido-4-cyano-1-N-phenethylpiperidinocarbonylpyrazole.
43	3-formamido-4-cyano-1-N-(p-diethylaminoethyl)piperidinothiocarbonylpyrazole.
44	3-acetamido-4-cyano-1-N-(p-pyrrolidinethiyl)piperidinothiocarbonylpyrazole.
45	3-acetamido-4-cyano-1-N-(p-butoxycarbonyl)piperidinothiocarbonylpyrazole.
46	3-acetamido-4-cyano-1-N-[3,4-di(2-hydroxyethyl)piperidino]carbonylpyrazole.
47	3-formamido-4-cyano-1-N-o-tolylethylpiperidinocarbonylpyrazole.

The above examples can be repeated to obtain other compounds with the scope of this invention by appropriate selection of reactants as will be readily understood in the art.

The invention claimed is:

1. A compound selected from compounds of the formula

5

where

X is selected from the group consisting of oxygen and sulfur;

A is selected from the group consisting of

10

wherein R₁ is methyl; and R₂ is selected from the group consisting of alkyl of 1 through 6 carbons where the alkyl is joined to the carbamyl nitrogen by a carbon selected from the group consisting of a primary and a secondary carbon of said alkyl; alken-2-yl of 3 through 6 carbons where the alken-2-yl is joined to the carbamyl nitrogen by a carbon selected from the group consisting of a primary and a secondary carbon of said alken-2-yl; alken-2-yl of 3 through 6 carbons where the alken-2-yl is joined to the carbamyl nitrogen by a carbon selected from the group consisting of a primary and a secondary carbon of said alken-2-yl; alkoxyalkyl of 2 through 6 total carbons; dimethylamino; and dialkylaminoalkyl where each of the alkyl groups in the dialkyl portion has 1 through 2 carbons and the remaining alkyl group has 1 through 4 carbons with a total of 3 through 7 in said dialkylaminoalkyl group;

morpholino;

pyrrolidino;

piperidino;

dehydropiperidino;

azabicyclononidino; and

a substituted piperidino group of the structure

40

wherein Y₁ is selected from the group consisting of hydrogen and methyl; Y₂ is selected from the group consisting of hydrogen, methyl, ethyl and —COOR₅ where R₅ is alkyl of 1 through 4 carbons; and Y₃ is selected from the group consisting of hydrogen, alkyl of 1 through 6 carbons, hydroxyalkyl of 2 through 6 carbons, trifluoromethyl, —COOR₆ where R₆ is alkyl of 1 through 4 carbons, dialkylaminoalkyl of 3 through 7 carbons where each of the alkyl groups in the dialkyl portion has 1 through 2 carbons and the remaining alkyl group has 1 through 4 carbons, pyrrolidinomethyl, and hydrocarbon aralkyl of 7 through 9 carbons; and R₃ is selected from the group consisting of hydrogen, formyl, acetyl and propionyl.

45

50

55

2. A compound as set forth in claim 1 wherein

where R₁ is methyl and R₂ is alkyl of 1 through 6 carbons joined to the carbamyl nitrogen by a secondary carbon of the alkyl, R₃ is selected from the group consisting of formyl, acetyl and propionyl, and X is oxygen.

3. A compound as set forth in claim 1 wherein A is a heterocyclic group as defined in claim 1.

4. A compound as set forth in claim 1 wherein A is a 4-mono-substituted piperidino group as defined in claim 1.

5. A compound as set forth in claim 1 wherein A is piperidino, R₃ is selected from the group consisting of formyl, acetyl and propionyl, and X is oxygen.

6. A compound as set forth in claim 1 wherein A is piperidino, R₃ is selected from the group consisting of formyl, acetyl and propionyl, and X is oxygen.

7. 1-N-(4-methylpiperidino)carbonyl-3(5)-formamido-4-cyanopyrazole.

8. 1-N-(4-methylpiperidino)carbonyl-3(5)-acetamido-4-cyanopyrazole.

9. 1-N-(4-methylpiperidino)carbonyl - 3(5) - propionamido-4-cyanopyrazole.

10. 4-cyano-1-N,N-dimethylcarbamyl-3(5)-formamido-pyrazole.

11. 3(5)-acetamido-4-cyano-1-N,N-dimethylcarbamyl-pyrazole.

12. 4-cyano-3(5)-formamido-1-N-isopropyl-N-methylcarbamylpyrazole.

13. 3(5)-acetamido-4-cyano-1-N-isopropyl-N-methylcarbamylpyrazole.

14. 1-N-sec-butyl-N-methylcarbamyl-4 - cyano - 3(5)-formamidopyrazole.

15. 3(5)-acetamido-1-N-sec-butyl-N-methylcarbamyl-4-cyanopyrazole.
